UNITED STATES PATENT OFFICE

WILLIAM H. PATTERSON, OF NEW ORLEANS, LOUISIANA.

FIREPROOF DOOR OR SHUTTER.

1,307,876.

Specification of Letters Patent. Patented June 24, 1919.

Application filed November 29, 1916. Serial No. 134,085.

To all whom it may concern:

Be it known that I, WILLIAM H. PATTERSON, a citizen of the United States, residing at New Orleans, in the parish of Orleans and 5 State of Louisiana, have invented new and useful Improvements in Fireproof Doors or Shutters, of which the following is a specification.

My present invention pertains to fire-proof doors or shutters, the term "door" as 10 hereinafter employed being intended to comprehend shutters and other closures as well as sliding and swinging doors.

My said invention contemplates the provision of an efficient fire-proof door, susceptible 15 of being cheaply manufactured, and constructed in such manner that it is finished in appearance and yet is well adapted to prevent the transmission of heat from one of its sides 20 to the other and is otherwise enabled to withstand the action of a high degree of heat without warping or twisting or other deterioration.

With the foregoing in mind the invention 25 will be fully understood from the following description and claims when the same are read in connection with the drawings, accompanying and forming part of this specification, in which:

30 Figure 1 is a front elevation of a sliding door constructed in accordance with my invention and equipped with the usual appurtenances.

Fig. 2 is an enlarged detailed horizontal 35 section taken in the plane indicated by the line 2—2 of Fig. 1.

Fig. 3 is a similar view on the line 3—3 of Fig. 1.

Fig. 4 is a detail horizontal section illustrating 40 the upright expansion bars comprised in the door.

Fig. 5 is a detailed vertical section taken on the line 5—5 of Fig. 1.

Fig. 6 is a detail vertical section showing 45 the horizontal reinforcing member hereinafter specifically referred to.

Fig. 7 is a detail vertical section showing 50 the relative arrangement of the asbestos filler, while Fig. 7^a is an elevation showing the corner castings, side stiles and base and crown bars of the door in proper relative arrangement.

Figs. 8, 9, 10, 11 and 12 are views of modifications hereinafter specifically referred to.

Referring by numeral to said drawings 55 and more particularly to Figs. 1 to 7^a, thereof:

1 is an overhanging track, and 2, 2, are hangers through the medium of which my novel door is suspended from the track in 60 the ordinary well-known manner.

As will be readily understood by comparison of Figs. 1 to 7^a, the door comprises a rectangular frame, the side stiles 3, the base bar 4 and the crown bar 5 of which are hollow, and are provided with inwardly-directed flanges 6.

Extended between and connected with the said stiles and bars of the door frame are spaced sheet-metal walls 8; the said walls being provided with upright corrugations, preferably though not necessarily, of obtuse angle form in horizontal section, and arranged with the said corrugations in opposed relation as shown in Figs. 2, 3 and 4, 75 so as to afford air spaces of considerable size. The said walls 8 extend between the flanges of the side stiles 3, but by reference to Figs. 5 and 7, it will be noted that the walls extend outside of and lap the flanges 80 of the base bar 4 and the crown bar 5, with the result that the construction is finished in appearance and is calculated to prevent moisture gaining access to the interior of the door.

The walls 8 are formed in sections, Figs. 1 and 4, and the sections of each wall are joined through the medium of expansion bars 9 (one or more). The said expansion bars are disposed vertically and are respectively formed by interlocking portions of adjoining wall sections as best shown in Fig. 4. Manifestly the said bars permit of expansion and contraction of the walls without warping or twisting thereof.

Arranged between the walls 8 and extending throughout the area of the door is an asbestos sheet 10 which serves in conjunction with the closed air space to prevent the transmission of heat from one wall to the other.

Extending between and riveted or otherwise fixedly connected to the opposed walls 8 and arranged at an intermediate point in the height of the door is a reinforcing strip 11 formed by bending a sheet of metal upon itself. The said strip 11 in addition to stiffening and lending increased rigidity and

- strength to the door, assists in maintaining the walls in opposed and spaced relation. It is to be understood in this connection that the strip 11 is riveted or otherwise connected 5 to the flanges 6 of the side stiles 3. It will also be noticed by reference to Fig. 7 that the asbestos sheet 10 is secured by rivets between the flanges 6 of the crown bar 5 from which it is hung with its side edges resting 10 adjacent to the flanges 6 of stiles 3, Fig. 2, and its lower edge resting adjacent to the flanges 6 of the base bar 4, Fig. 5.
- Castings 12 are disposed in the lower and upper corners of the door as will be understood 15 by comparison of Figs. 3, 5 and 7^a which show the arrangement of the castings within and between the side stiles 3, on the one hand, and the base bar 4 and crown bar 5, on the other.
- 20 The corner castings 12 respectively comprise the major right-angle portion, of H-form in cross section, shown by full lines in Figs. 3 and 5 and by dotted lines in Fig. 7^a, and a shank or web 13 which extends between 25 the outer ends of the arms of the right angle portion and is designed to rest between the flanges 6, and also between the walls 8 and alongside the pendent asbestos sheet 10. Each corner casting also comprises 30 a corner block 12^a against which the end of one side stile 3 and one horizontal bar (base bar 4 or crown bar 5) abut as clearly shown in Fig. 7^a. By virtue of the said construction and relative arrangement, 35 the corner castings 12 lend great stiffness and strength to the door and preclude sagging of the same as well as distortion or other deterioration when the door is subjected to the action of a high degree of heat.
- 40 The said corner castings 12 also prevent injury to the door when it brings up against a stop (not shown), and in this the said castings are assisted by the reinforcing bar 11. The corner castings are connected with 45 the said frame bars of the door by rivets which extend through the flanges of the frame bars and the shanks or webs of the corner castings, and this assists materially in the described capacity of the corner castings.
- 50 As will be seen by comparison of Figs. 2 and 7, an asbestos filler 14 is arranged between the flanges 6 of each side stile and the flanges 6 of the crown bar 5 and the base bar 4. The asbestos filler in the base bar 4 is not shown, but it will be readily understood that its arrangement relative to the flanges of the base bar 4 is the same as its arrangement relative to the flanges of the crown bar 5.
- 60 Each asbestos filler 14 occupies the space between adjoining ends of the flanges 13 of corner castings 12, and serves the important purpose of filling the space between and holding the flanges 6 apart at the points between 65 the several corner castings 12.

In Figs. 8, 9 and 10 is shown a swinging door similar in construction to the sliding door shown in Figs. 1-7^a; Fig. 9 being taken in the plane indicated by the line 9—9 of Fig. 8, and Fig. 10 comprising a finished portion of the door together with one corner casting, one hollow frame bar and an assembly of one frame bar, the opposed walls and the interposed asbestos sheet. The said swinging door is arranged to close against a hollow frame 15, as shown in Figs. 8 and 9.

In the modification shown in Fig. 11 no corner castings are employed. On the other hand the side stile 3^a and the horizontal bar 5 that meets the same are brazed so as to make a seamless joint at 16.

In the modification shown in Fig. 12, corner castings are employed, but the same are different in construction and arrangement from the corner castings of Figs. 1 to 10. The modified corner casting 12^x has solid major portions disposed at right angles to each other, and a shank or web 13^x extending between the end portions of the major arms or portions. The said solid portions 12^x are arranged in the meeting stile and horizontal bar of the frame, while the web or shank 13^x is arranged and secured between the flanges of the frame members, with the result that the door is braced and strengthened almost if not quite to the extent that obtains in the construction shown in Figs. 1 to 7^a.

Having described my invention, what I claim and desire to secure by Letters-Pat-ent, is:

1. A fire-proof door or shutter comprising a frame having side stiles and base and crown bars; and spaced walls of corrugated sheet-metal arranged in said frame and connected therewith; each of said walls being formed of sections the adjacent portions of which are interlocked and connected together by the interlocking, whereby expansion bars are formed in the walls, in combination with a reinforcing strip, of sheet-metal bent upon itself, extending between and connected to opposite frame portions and interposed between and connected to the spaced sheet-metal walls.

2. In a fire-proof door or shutter, the combination of a frame comprising a bottom bar, crown bar and hollow side stiles, each having inwardly-directed parallel flanges, and corner castings arranged within and between the side stiles on the one hand, and the base bar and crown bar, on the other, and having webs resting between and connected to the inwardly-directed flanges of said stiles and bars; asbestos fillers interposed between and connected to the flanges on the frame stiles and bars and extending and occupying the spaces between the webs of the corner castings, spaced sheet-metal walls arranged in and carried by said frame; the

said walls extending between and being connected with the inwardly-extending flanges of the side stiles, and resting outside of and being connected with the inwardly extending flanges of the base bar and crown bar, and a pendent asbestos sheet resting between the sheet-metal walls and adjacent and in spaced relation to the base bar and the side stiles and having its upper end portion interposed and secured between the flanges of

the crown bar, whereby it is suspended from said bar.

In testimony whereof I have hereunto set my hand in presence of two subscribing witnesses.

WILLIAM H. PATTERSON.
